Patented June 26, 1962

193,102

PORTABLE ELECTRIC BELT GRINDING MACHINE

Morton S. De Groff, Bryan, Ohio, assignor to The Aro
Corporation, a corporation of Ohio

Filed Sept. 19, 1960, Ser. No. 62,186

Term of patent 14 years

(Cl. D37—1)

FIG. 1 is a front perspective view of a portable electric belt grinding machine showing my new design;

FIG. 2 is a rear perspective view thereof; and
FIG. 3 is a top plan view thereof.

I claim:

The ornamental design for a portable electric belt grinding machine, substantially as shown.
